Primary Examiner — Mark Goodwin(74) *Attorney, Agent, or Firm* — Foley & Lardner LLP(57) **CLAIM**

We claim the ornamental design for a sealing gland, as shown and described.

DESCRIPTION

FIG. 1 is a top, front perspective view of a sealing gland showing our new design;

FIG. 2 is a bottom, front perspective view thereof;

FIG. 3 is a top plan view thereof;

FIG. 4 is a bottom plan view thereof; and,

FIG. 5 is a front elevation sectional view thereof.

The broken lines in the drawings form no part of the claimed design. Broken lines formed by equal length dashes show unclaimed subject matter. Cross-hatching in sectional views indicates a sectioned portion unlimited by material; the cross-hatching itself is not part of the claimed design.
